UNITED STATES PATENT OFFICE

JOHN D. BILLINGS, OF NEW YORK, N. Y., ASSIGNOR TO THE SOUTHERN HORSE AND MULE SHOE MANUFACTURING COMPANY, OF STRASBURG, VIRGINIA.

MACHINE FOR FORMING HORSESHOE-BLANKS.

SPECIFICATION forming part of Letters Patent No. 498,839, dated June 6, 1893.

Application filed June 14, 1892. Serial No. 436,701. (No model.)

To all whom it may concern:

Be it known that I, JOHN DOUGLAS BILLINGS, a citizen of the United States, residing at the city of New York, in the county of New York and State of New York, have invented certain new and useful Improvements in Machines for Forming Blanks for Use in the Manufacture of Horseshoes, of which the following is a specification.

- 10 My present invention relates in general to that type of machines for forming blanks for horseshoes, which are provided with complementary reciprocating and rotary dies for rolling hot metal bars into blanks provided with 55 calks and with indentations for nail holes and suitable for being cut up and bent into horseshoes; and it relates more particularly to mechanism for driving or actuating the complementary dies.
- 20 The principal objects of my present invention are first, to provide mechanism for uniformly operating or driving the dies until one or more blanks adapted to be cut up into pieces corresponding to the length of one or 60 25 more horseshoes have been formed, and for automatically stopping the dies as soon as the above result has been accomplished, whereby the blanks are rolled of uniform length and waste of rolled metal in cutting up the 65 30 same is avoided; second, to provide simple, inexpensive and efficient means under the control of the operator for rapidly returning the dies to their normal positions upon the completion of a single or series of blanks; third, to provide simple devices for checking the return motion of the dies as soon as the latter are in their proper initial positions; and fourth, to cause the rotary and reciprocating dies to travel uniformly with precisely 70 35 40 the same surface velocity, thus preventing one of the dies from lagging or dragging behind the other and insuring the production of perfect work.

My invention consists of a machine for forming metal bars into horseshoe blanks provided with complementary reciprocating and rotating dies, a positively driven gear-wheel and suitable gearing interposed between said gear-wheel and each of said dies.

45 50 My invention further consists of a machine

for forming metal bars into horseshoe blanks provided with complementary reciprocating and rotating dies, a countershaft, gear wheels interposed between the rotary die and counter-shaft, a rack and pinion interposed between the reciprocating die and counter-shaft, and means for actuating the counter-shaft, whereby said dies are conjointly driven in the same direction with a uniform surface velocity.

55 My invention further consists of a machine for forming bars into horseshoe blanks provided with complementary reciprocating and rotating dies, an intermediate gear-wheel, spur gearing interposed between said intermediate gear-wheel and each of said dies, a main-shaft, a driving gear, a friction clutch and a starting lever.

60 My invention further consists of a machine for forming metal bars into horseshoe blanks provided with complementary reciprocating and rotary dies, mechanism for actuating said dies, and means for automatically throwing said mechanism out of action at a predetermined point in the travel of the dies, whereby the blanks are automatically rolled of uniform and proper length.

65 My invention further consists of a machine for forming metal bars into horseshoe blanks provided with complementary reciprocating and rotary dies, a counter-shaft geared to each of said dies, a driving shaft, and friction clutches and their accessories for connecting the driving shaft with the counter-shaft and with the rotary die, whereby the dies are operated more rapidly in one direction than the other; and my invention further consists of the improvements hereinafter described and claimed.

70 75 80 The nature, characteristic features and scope of my invention will be more fully understood from the following description taken in connection with the accompanying drawings forming part hereof; and in which—

85 90 95 Figure 1, is a side elevation of a machine for forming blanks for use in the manufacture of horseshoes embodying features of my invention and showing gearing for driving the complementary dies during the formation of a blank. Fig. 2, is a top or plan view of 100

the machine showing devices for automatically checking the movement of the dies at the respective ends of their travel. Fig. 3, is a similar view to Fig. 1, showing the other side of the machine and illustrating means for rapidly returning the dies to their initial positions. Fig. 4, is an end view of the machine showing the main and counter shafts and their accessories. Fig. 5, is a sectional view taken on the line 5—5, of Fig. 6, and illustrating the detail construction of one type of rotary and reciprocating dies and also showing a horseshoe blank formed by said dies and adapted for use in the production of hind shoes. Fig. 6, is a front elevational view showing at the left hand side thereof dies adapted to produce blanks for hind shoes and at the right hand side thereof dies adapted to produce blanks for front shoes. Fig. 7, is a top or plan view of the hind shoe blank illustrated in Fig. 5. Fig. 8, is a transverse section taken on the line 8—8, of Fig. 7; and Fig. 9, is a transverse section of a front shoe blank such as is produced by the dies shown at the right hand side of Fig. 6, illustrating the same provided with the required bevel.

In the drawings *a*, is a main frame provided with horizontal ways *a'*, and with standards *a''*. A revoluble die or set of similar dies is formed upon the periphery of a cylinder *b* keyed or otherwise rigidly connected with a shaft *b'*, journaled in the standards *a''*. *c*, is a reciprocating die or set of similar dies carried by a table *d*, working in ways *a'*. The dies *c*, may be flat or inclined. When the die is flat as shown at the left hand side of Fig. 6, it is useful in the production of a blank *x*, Fig. 8, for hind shoes, and when it is inclined as shown at the right hand side of Fig. 6, it is useful in the production of a blank *x'*, Fig. 9, for front shoes. The dies of the cylinder *b*, Figs. 5 and 6, are located between flanges *y*, that overlap the dies *c*, of the table *d*, and comprise recesses *y'*, in which the calks *x''*, are formed, creasers *y''* and projections *y'''*, that form the groove *x''* and nail hole cavities *x'''*, and a spur *y''''* that indents the blank as at *x''''*, and thus facilitates the operation of cutting the same into shoe lengths. By the employment of these dies horse and mule shoes can be rapidly and perfectly made, and from one to six shoe-bars of different kinds or forms and adapted to be cut up into three or more calked or continuous calked or plain shoes can be made at the same time and by one revolution of the cylinder *b*, and a corresponding movement of the table *d*, because these differently shaped dies can be provided on the cylinder. In my Patent No. 422,564 of March 4, 1890, one set of dies having contours adapted for such purposes are shown and described, but my present invention is not limited to the employment thereof.

e, is a counter-shaft journaled in the main frame *a*, and provided with a pinion *e'*, Fig. 4, engaging a rack *f*, for operating the recip-

rocating die and with a gear-wheel *e''*, meshing with a gear *f'*, keyed to one end of the shaft *b'*.

The main driving shaft *g*, of the machine is journaled in the frame-work *a*, and is revolved continuously in the direction indicated by the arrow in Fig. 1, by means of a pulley and belt, or other power appliance, (not shown.)

h, is a driving gear loosely mounted upon the shaft *g*, and provided with one member *h'*, of a friction clutch, whereof the other member *h''*, is splined onto the shaft *g*, so that when the two parts *h'* and *h''*, of the friction clutch, are in engagement with each other, motion is transmitted from the driving shaft *g*, to the counter-shaft *e*, through the intervention of the gears *h* and *e''*, and from the counter-shaft to the die *c*, through the intervention of the rack *f*, and pinion *e'*, and to the die of the cylinder *b*, through the intervention of the gears *e''* and *f'*, so that the intermediate wheel or gear *e''*, drives both of the dies through the intervention of suitable gearing.

During the rolling operation the iron bar may and in practice usually does offer more resistance to the movement of one of the dies than to the movement of the other of them, so that if the necessary motion were transmitted to one of the dies and from it through the intervention of suitable gearing to the other, the result would be that one of the dies would tend to lag behind the other, whereby the calks and indentations would be displaced and the blanks rendered useless.

In my invention the wheel *e''*, is positively driven and imparts its motion through the intervention of distinct and separate mechanism to the respective dies, so that the latter are independently driven but are constrained to move in unison, thus insuring the proper relative disposition of the calks and indentations in the finished blanks.

i, is an upright rock-shaft carried by the frame-work *a*, and provided at one extremity with an arm *i'*, connected with the member *h''*, of the friction clutch and at the other extremity with a tappet arm *i''*.

j, is a starting lever pivotally connected with the frame-work *a*, and adapted to engage the tappet arm *i''*, in order to throw the member *h''*, of the friction clutch into position for effecting the forward or operative movement of the dies through the intervention of the driving gears.

i'', is a projection or stop carried by the rear portion of the table *d*, and adapted to be shifted by the forward motion thereof into contact with the tappet arm *i''*, whereby the latter is shifted into position for disengaging the respective members *h'* and *h''*, of the friction clutch, thus automatically throwing the driving gear out of action. By these means the dies are automatically stopped as soon as they have completed the operation of rolling a series of blanks suitable for being cut up

into a number of lengths which after bending form perfect horseshoes. Thus the waste of material due to cutting off the uneven ends that would occur if the dies were permitted to roll blanks of various lengths, is avoided.

5 *k*, Fig. 3, is a pulley mounted loose upon the driving shaft *g*, and provided with one member *l*, of a friction clutch, whereof the other member *l'*, is splined onto the shaft. 10 This pulley *k*, serves to impart motion to a pulley *m*, keyed to the shaft *b'*, through the intervention of a crossed belt *n*, whereby the dies may be returned rapidly to their normal or initial position.

15 *o*, is an upright rock-shaft provided at its lower extremity with a radial arm *o'*, carrying the member *l'*, of the friction clutch, and at its upper extremity with a tappet arm *o''*.

20 *p*, is a reversing lever pivotally connected with the frame-work *a*, and adapted to engage with the tappet-arm *o''*, and thus throw the member *l'*, of the friction clutch, into action, whereupon the dies are returned to their initial positions through the instrumentality of 25 the crossed belt *n*, and its complemental pulleys, gear-wheels *f'* and *e²*, rack *f*, and pinion *e'*.

30 *o³*, is a lug carried by the forward portion of the table *d*, and adapted to collide with the tappet-arm *o''*, in order to shift the same into position for throwing the member *l'*, of the clutch out of engagement as soon as the dies have been brought to their initial positions.

The mode of operation of the hereinabove described machine is as follows:—Assuming that the parts are in the position illustrated in Fig. 1, a number of bars of metal are placed side by side upon the table *d*, whereupon the starting lever *j*, is depressed, thus 35 throwing the gears *h*, *e²* and *f'*, into action and causing the dies to roll the bars into horseshoe blanks. As soon as the blanks have attained the requisite length for being 40 cut up into pieces adapted to be bent into complete horseshoes, the lug *i³*, by contacting with the tappet-arm *i²*, automatically throws the gears *h*, *e²* and *f'* out of action, whereupon the movement of the dies is checked. After the finished blanks have been removed 45 from the table *d*, the reversing lever *p*, is depressed. This movement of the reversing lever throws the member *l'*, of the clutch, into engagement with the member *l* thereof, so that the dies are run rapidly in a reverse direction through the instrumentality of the 50 crossed belt *n*, and its accessories. As soon as the dies have regained their original or initial positions the lug *o³*, by contacting with the tappet-arm *o''*, automatically throws the member *l'*, of the clutch, out of action with the 55 result that the dies and table *d*, are brought to rest in position for effecting the formation of a second series of horseshoe blanks in precisely the manner hereinabove described.

60 It will be obvious to those skilled in the art to which my invention appertains that modifications may be made in details without

departing from the true spirit thereof, hence I do not limit myself to the exact construction and arrangement of parts hereinabove set forth, but

Having thus described the nature and objects of my present invention, what I claim as new, and desire to secure by Letters Patent, is—

75 1. A machine for forming bars into horseshoe blanks provided with a positively driven counter-shaft having two gear-wheels, whereof one imparts motion to a rack attached to a reciprocating table provided with a die, and whereof the other drives a gear-wheel attached to a revolute drum or cylinder provided with a die, the construction and arrangement being such that the dies are each driven by the counter-shaft through separate gearing, whereby lagging of one of the dies in respect to the other is obviated, substantially as and for the purposes set forth.

2. A machine for forming bars into horseshoe blanks provided with a reciprocating table having a rack and a die, a revolute cylinder or drum having a gear-wheel and a die, a counter-shaft provided with a pinion meshing with said rack and with a gear as *e²*, meshing with the gear-wheel of the cylinder, 95 a main-shaft provided with a gear-wheel for driving the gear *e²*, and means for operating the main-shaft, substantially as and for the purposes set forth.

3. A machine for forming bars into horseshoe blanks provided with a reciprocating table having a rack and a die, a revolute cylinder having a gear-wheel and a die, a counter-shaft provided with a pinion meshing with said rack and with a gear, as *e²*, meshing with the gear-wheel of the cylinder, a main-shaft provided with a gear-wheel, as *h*, for driving the gear *e²*, and a friction clutch and starting-lever for connecting and disconnecting the gear-wheel *h*, and the main-shaft, 100 substantially as and for the purposes set forth.

4. A machine for forming bars into horseshoe blanks provided with a reciprocating table having a die, a revolute cylinder having a die, a main-shaft, a counter-shaft operated by the main-shaft for driving said table forward through the intervention of a rack and pinion and for driving said cylinder in a corresponding direction through the intervention of gears *e²* and *f'*, a crossed-belt and its complemental pulleys for imparting motion of the main-shaft to said dies to drive them in a reverse direction, and friction-clutches and their complemental reversing levers, substantially as and for the purposes set 115 forth.

5. A machine for forming metal bars into horseshoe blanks provided with a reciprocating table having a die, a revolute cylinder having a die, a gear-wheel *e²* for driving said table in one direction through the instrumentality of a rack and pinion and for driving said cylinder in a corresponding direction through the instrumentality of a gear-

- wheel f' , a gear-wheel h , for driving the gear-wheel e^2 , a crossed-belt and pulleys for driving said cylinder in a reverse direction, where-by the table is driven through the gear-wheel 5 f' and e^2 in a similar direction, and tappet-arms and their complemental link-work and friction-clutches for throwing said belt and gear h , out of and into engagement with the main-shaft at a predetermined point in the 10 travel of the dies, substantially as and for the purposes set forth.
6. A machine for forming bars into horse-shoe blanks provided with complemental reciprocating and rotating dies, a driving-shaft, 15 mechanism adapted to move the dies in one direction and comprising gear-wheels h , e^2 and f' , and a counter-shaft e , a rack f and pinion e' , a crossed-belt n and pulleys m and k for driving said dies in a reverse direction, 20 friction-clutches for connecting and disconnecting the gear-wheel h , and the driving-pulley with a positively driven main shaft, and tappet-arms operated by the reciprocating die and adapted to throw the clutch of the wheel 25 f' , out of action at one end of the stroke of the dies and to throw the clutch of the driving pulley out of action at the other end of the stroke, and starting levers for throwing said clutches into action, substantially as and 30 for the purposes set forth.
7. The combination, in a machine for forming metal bars into horseshoe blanks, of complemental reciprocating and revoluble dies, a counter-shaft, gear-wheels e^2 and f' , interposed between the counter-shaft and revoluble die, a rack and pinion interposed between the reciprocating die and counter-shaft, a main-shaft provided with a loose gear-wheel meshing with the gear wheel e^2 , and with a 35 40 friction-clutch for the loose-gear-wheel, a driving pulley loose on the main-shaft and connected by a crossed-belt with the revoluble die, a friction-clutch for said driving-pulley, and means for operating said friction-clutches, substantially as and for the purposes set forth. 45
8. The combination, in a machine for forming metal bars into horseshoe blanks, of a revoluble die cylinder provided at one extremity with a gear-wheel and at the other extremity with a pulley, a reciprocating table 50 provided with a rack and a die, a driving-shaft provided with a loose pulley connected with the pulley on the cylinder by a crossed-belt, a counter-shaft provided with a pinion engaging said rack, a gear-wheel loose on the 55 main-shaft, an intermediate gear-wheel keyed to the counter-shaft and meshing with the gears on the main and cylinder shafts, and means for operating said friction clutches, substantially as and for the purposes set forth. 60
9. In a machine for forming bars into horse-shoe blanks, a rotating die, a reciprocating table provided with a die, a driving shaft, spur gearing for actuating the rotating die and table in one direction, a crossed belt and 65 complemental pulleys for actuating the rotating die and table in a reverse direction, friction clutches, rock-shafts provided with arms engaging said clutches and with tappet-arms, tappet-lugs, stops or projections at the 70 respective extremities of the table for automatically operating the tappet-arms, and starting and reversing levers, substantially as and for the purposes set forth.

In witness whereof I have hereunto set my 75 signature in the presence of two subscribing witnesses.

JOHN D. BILLINGS.
